GRAVE MARKER

William C. Vogelpohl, Belleville, Ill.

Application November 30, 1931
Serial No. 578,073

2 Claims. (Cl. 40—124.5)

This invention relates to grave markers and has for an object to provide a device of this character which will include an anchor, a detachable bracket or holder for a flower bowl or glass jar, a bracket for an organization emblem or the like, a bracket for a national flag, and a name plate holder, all assembled as a unitary integral structure with the anchor or ground stake.

- 10 A further object of the invention is to provide a grave marker in which all of the various parts, above enumerated, may be formed of sheet metal and may be assembled easily and quickly without the use of complicated tools.
- 15 A still further object is to provide a grave marker of the above described type which will be formed of a few simple, durable and inexpensive parts which will not easily get out of order.

20 With the above and other objects in view, the invention consists in certain novel details of construction and combinations of parts hereinafter fully described and claimed, it being understood that various modifications may be resorted to within the scope of the appended claims without departing from the spirit or sacrificing any of the advantages of the invention.

25 In the accompanying drawing forming part of this specification:

30 Figure 1 is a perspective view of my improved grave markers.

Fig. 2 is a fragmentary cross sectional view through the bouquet bracket, the anchor and the name plate holder.

35 Fig. 3 is a fragmentary rear elevation of the device with the bouquet holder or bracket broken away, and

Fig. 4 is a cross sectional view taken on the line 4—4 of Fig. 2.

40 Referring now to the drawing in which like characters of reference designate similar parts in the various views, 10 designates an anchor or ground stake which is preferably formed of sheet metal bent to provide a channel, the top of which is expanded, as best shown in Fig. 2, to provide a substantially curved plate 11. In further carrying out the invention, I provide a bouquet bracket 12 comprising a substantially Z-shaped length of strip metal 13, one leg of which is passed into the channel of the ground stake 10 and thence bent downwardly along the web of the channel between the flanges thereof, as best shown in Fig. 2, a bolt 14 being passed through the flanges at the bight of the length of strip metal to support the bracket at a desired height on the ground stake. A cotter pin 15 is passed also through the

50 web of the ground stake and through the lower end of the bracket to removably secure the bracket in place, this cotter pin coacting with a pair of lips 16 which are struck from the flanges of the channeled ground stake and overlie the lower portion of the bracket to removably secure the bracket in place. A substantially U-shaped length 17 of strip metal straddles the Z-shaped length of strip metal 13 and is riveted thereto, as shown at 18. A bouquet holder, such as a Mason glass jar, may obviously be inserted between the plate 11 of the ground stake and the upstanding free ends of the U-shaped and Z-shaped lengths of strip metal.

55 In further carrying out the invention, I provide a combined name plate holder and emblem holder comprising a plate 19 of sheet metal which is arranged transversely across the plate 11 of the ground stake and will be removably secured

60 thereto by means of a pair of vertically arranged cotter pins 20 which are passed through suitable registering openings in both plates. Rivets may

65 also be used in lieu of the cotter pins, or other suitable connectors may be used, if desired. It will be observed that a pair of flanges 21 and 22

70 are bent inwardly from the upper edge of the back plate 19. It will also be observed that a pair of flanges 23 and 24 are struck from the back plate and underlie the respective flanges 21 and 22.

75 Also, a pair of flanges 25 and 26 are bent from the bottom edge of the back plate 19 to underlie the flanges 23 and 24.

80 The vertically aligned flanges 21 and 23, on one side of the back plate, are preferably provided with square openings 27 to receive the staff of a flag 28, the staff being supported upon the corresponding underlying, imperforate flange 25, as

85 shown in Fig. 1.

90 The vertically aligned flanges 22 and 24, on the opposite side of the back plate, are preferably provided with registering square openings 28 to receive the staff of an emblem 29 or other organization insignia, the bottom of the staff being supported upon the corresponding underlying flange 26.

95 In further carrying out the invention, I provide a name plate holder comprising a sheet metal backing 30 the ends and top edges of which are bent inwardly over the backing to provide an upper retaining flange 31 and end retaining flanges 32, as best shown in Fig. 1. The metal

100 backing is preferably removably secured to the back plate 19 by cotter pins 33 arranged on opposite sides of the ground stake 10. However, other

105

110

suitable connectors may be employed in lieu of the cotter pins 33.

The retaining flanges 31 and 32 overlap a celluloid cover sheet 34 which overlies a name card 35 upon which may be inscribed suitable identifying data. Either one or a plurality of celluloid cover sheets may be employed to suitably protect the data card. The data card and cover sheet are preferably mounted in place by slipping the same upwardly between the retaining flanges 32 until in contact with the top retaining flange 31 whereupon a pair of cotter pins 36 may be passed through suitable openings in the backing and in the back plate 19 to engage the bottom edge 15 of the sheet and card with the heads of the cotter pins overlying the front face of the sheet, as best shown in Figs. 1 and 3.

From the foregoing description, it will be seen that I have provided a grave marker embodying a ground stake upon which a bouquet holder or bracket is removably secured, that also there are disposed on opposite sides of the bouquet bracket suitable brackets for receiving a flag and organization emblem or other identifying insignia, and that there is also included in the assembly an identification card holder.

Since the parts are all formed of sheet metal, long life and durability of the marker will be insured while decreased cost of manufacture will 30 be promoted so that markers may be turned out

in quantity for military graves, or the like, at minimum cost.

What is claimed is,

1. A grave marker including a ground stake, a back plate carried thereby, means extending through said plate and the stake detachably connecting the plate thereto and removable forwardly through the plate, and a metal backing carried by said back plate and overlying the forward ends of said means to limit said means against accidental displacement, said backing being provided with means to receive an identification card. 80

2. A grave marker including a ground stake, a back plate carried thereby, fastening devices extending through the plate and stake detachably connecting the plate thereto, said fastening devices being removable forwardly through the plate, a metal backing carried by the back plate and overlying the forward ends of said fastening devices, and fastening devices extending through said backing and back plate detachably connecting the backing thereto, said fastening devices being removable forwardly through the backing and said backing being provided with means to receive an identification card overlying the forward 100 ends of the latter fastening devices limiting the latter fastening devices against accidental displacement. 90
